United States Patent Office.

EDWARD HARRISON, OF SPRINGFIELD, OHIO.

Letters Patent No. 69,428, dated October 1, 1867.

IMPROVEMENT IN BEE-HIVES.

The Schedule referred to in these Letters Patent and making part of the same.

TO ALL WHOM IT MAY CONCERN:

Be it known that I, EDWARD HARRISON, of Springfield, in the county of Clark, and State of Ohio, have invented a new and useful Improvement in Bee-Feeders; and I do hereby declare the following to be a full, clear, and exact description of the same, reference being had to the accompanying drawings, in which—

Figure 1 is a vertical section of the feeder, showing its position on the hive.

Figure 2 is a vertical section of the same with its accompanying box; and

Figure 3 is a view of the strainer upon which the proper "feed" is to be placed when in use.

My invention consists in an improved "bee-feeder," to be used in connection with hives of any variety or pattern, and it consists in, first, the construction of the cylindrical cup, in which the proper "feed" is placed, together with the box or chamber on which it is supported; second, the arrangement of the strainer at the bottom of the cup, as specified.

In order that others may understand the operation and construction of my bee-feeder, I will proceed to particularly describe it.

Fig. 1 is a vertical section of the feeder attached to the top of an ordinary hive, and shows the manner of using. A A is an open-bottomed cup, of metal, glass, or other suitable material, containing the strainer D, (fig. 3,) held in place by the ring or band B of metal or other material fitting loosely within the cup A. The cup A may be used in connection with the box I I, and the whole placed upon the top of or within the upper chamber, as is represented in fig. 2. When in use the cup A is held in position in an opening on the top of the box or main chamber of the hive, of suitable shape and size to admit it readily, by means of the flange E, and the strainer is kept in place by its ring B pressing it closely against the inner surface of the cup A. The flange F, when viewed from below, is convex, which gives the "feed" a tendency toward the centre of the strainer, where the bees may have access to it. When properly prepared the "feed" will not pass through the strainer faster than removed by the bees below. The ring B, together with the strainer D, is easily removed from the cup by the handle C, in order to clean or renew the strainer, which is composed of cloth or other suitable fibrous material.

The construction and operation of the whole apparatus is very simple; it is not liable to get out of order; can be taken off and replaced in a moment's time; and is easily adapted to fit any hive, of whatever construction and form.

In using my feeder in winter it is best to place it as near the cluster of bees as possible, for it is well known to all observers of bees that during cold weather they remain clustered among the combs in the upper part of the main chamber of the hive, and will not leave the cluster unless forced to do so by hunger.

The cylindrical cup may be used without the box by placing it over a suitable opening in the honey-board. The outer flange E is not necessary to the operation of my invention, because the cup would not be very liable to removal if only resting upon the surface of the honey-board. The flange, however, is inexpensive, and makes the apparatus more perfect. When the outer flange is dispensed with the inner one should be placed a short distance from the bottom. This will cause the cup to rest more firmly on the honey-board. The cup A is provided with a cover to prevent access of bees, other insects, or dirt to the contents of the cup, and at the same time render it possible to replenish the feed without the removal of the cup or disturbance of the bees.

My feeder may be used at any season of the year. Bees will feed from it in the coldest weather with perfect success. Robbers cannot obtain access to the feed without passing through the cluster of bees in the hive, which they rarely, if ever, attempt.

Having described my invention, what I claim as new, and desire to secure by Letters Patent, is—

The open-bottomed cup A, in combination with a removable strainer, D, substantially as and for the purpose set forth.

In combination with the open-bottomed cup A, the ring B, for the purpose of readily applying or removing the strainer D, substantially as and for the purpose set forth and described.

A bee-feeding apparatus, which can be filled through the top, and from which the feed can only be obtained through the bottom, so that it may be placed to cover an orifice in the top of the hive, and the bees enabled to feed while observing their natural inclination to cluster together, and so that it may be replenished with feed without removal or disturbance of the bees, as set forth.

EDWARD HARRISON.
